BED SLAT CONSTRUCTION

Frank D. Collins, North Pelham, N. Y.

Application November 10, 1950, Serial No. 195,087

1 Claim. (Cl. 5—236)

1

This invention relates to bed slat construction. An object of this invention is to provide a bed slat construction wherein a series of slats are secured together by means of pivotally connected together links so that the intermediate slats will be disposed evenly apart from each other and from the end slats.

Another object of this invention is to provide a bed slat construction embodying linked together slats which are so constructed and arranged as to be prevented from lateral shifting.

A further object of this invention is to provide a bed slat construction which is simple in construction and can be readily mounted on conventional bed frames.

With the above and other objects in view, my invention consists in the arrangement, combination and details of construction disclosed in the drawings and specification, and then more particularly pointed out in the appended claim.

In the drawings:

Figure 1 is a bottom plan view of a bed slat construction embodying this invention.

Figure 2 is a fragmentary sectional view taken on the line 2—2 of Figure 1.

Figure 3 is an end elevation of the device in applied position showing the bed frame in section.

Figure 4 is a fragmentary sectional view taken on the line 4—4 of Figure 1.

Referring to the drawing, the numeral 10 designates a pair of end slats which are adapted to be engaged with the ends of a bed frame. These slats 10 are of like construction and are of inverted L-shape in transverse section having a horizontal upper side 11 and a flange or depending side 12. The opposite ends of the flange 12 are cut off as indicated at 13 thereby forming a lip or supporting tongue 14 which is adapted to overlie one of the side rails 15 of the bed frame. The cut-away end portions of the flanges 12 also provide a means whereby the end slats 10 will be held against endwise or lateral movement with respect to the bed rails 15.

A pair of T-shaped intermediate slats 16 are disposed between the end slats 10, and each intermediate slat 16 includes an upper side 17 and a depending flange or stem 18. The opposite ends of the depending flange 18 also are cut away as indicated at 18a so that the ends of the intermediate slats 16 will lie on the upper sides of the bed rails 15.

The end slats 10 are connected to an adjacent intermediate slat 16 by means of a pair of crossed links 19 which are pivotally connected together between the ends thereof as at 20. One of the

links 19 is pivotally connected as indicated at 21 to an end rail 10, and the other of the links 19 is pivotally connected as at 22 to the adjacent intermediate slat 16. The upper side 11 of the end slat 10 is provided with an elongated slot 23 within which a headed pin 24 carried by the opposite end of a link 19 is adapted to slidably engage. The adjacent intermediate slat 16 is also provided with an elongated slot 25 within which a headed pin 26 carried by the other of the links 19 is adapted to slidably engage. The two intermediate slats 16 have disposed therebetween a pair of links 27 pivotally connected together between the ends thereof as indicated at 28.

15 One end of each link 27 is pivotally connected as at 29 to an intermediate slat 16, and the other end of each link 27 is provided with a headed pin 30 which slidably engages in an elongated slot 31 carried by the upper side 17. The pivotally connected together links 19 and 27 provide a lazy tong connection between the slats 10 and 16 so that these slats will be held in parallel relation when extended or retracted.

In the applied position of the collapsible slat structure hereinbefore described the slats 10 and 16 are engaged with the rails 15 of the bed frame. The intermediate slats 16 will lie on the upper sides of the bed rails 15 being evenly spaced apart relative to each other and to the end slats 10.

With a bed slat construction as hereinbefore described the bed spring or other element normally engaged with the bed frame will be firmly and adequately supported at the end and between the ends thereof, and there will not be any possibility of any of the slats becoming disengaged from the bed frame or bed rails due to the fact that the slats are held against endwise movement or lateral movement with respect to the bed rails.

What is claimed is:

A bed slat construction comprising a pair of end slats of inverted L-shape in transverse section, one side of each slat being horizontal and the other side being vertical, said vertical side terminating at each end thereof inwardly of the ends of said horizontal side to thereby form slat supporting lips, spaced elongated slots in the horizontal sides of said end slats, a pair of intermediate slats of T-shape in transverse section, each including a horizontal upper side and a vertical stem, the opposite ends of said stems terminating inwardly from the ends of said upper sides to thereby form slat supporting lips, a first and second pair of pivotally connected together links, means pivotally connecting an end of one link of each pair to an end slat, means pivotally connect-

ing one end of the other link of each pair to an intermediate slat, said horizontal sides of the intermediate slats having elongated longitudinally extending slots formed therethrough in staggered relation on opposite sides of said stems, a third pair of pivotally connected together links, means pivotally connecting an end of one link of said third pair to an intermediate slat and means pivotally connecting one end of the other link of said third pair to the other intermediate slat and means comprising pins extending through said slots slidably connecting the opposite ends of said

links to said end and intermediate slats, the staggered relation of said slots providing a staggered relationship of adjacent pairs of links.
